UNITED STATES PATENT OFFICE

JENS P. NIELSEN AND JOSEPH R. RICHER, OF CHICAGO, ILLINOIS; SAID RICHER
ASSIGNOR TO SAID NIELSEN

END CLOSURE FOR FABRIC ROLLS

Application filed November 30, 1927. Serial No. 236,704.

The invention relates more particularly to means for closing and protecting the ends of rolled material such as roofing paper, etc. and to a method for attaching such means.

5 In shipping material of this type, it is customary to place within the bore of the roll a number of packages containing nails, washers, cement, etc., and to provide in combination with a pair of dished end plates 10 which serve to protect the ends of the roll, a tying means for securing the end plates and packages to the roll. This tying means has generally taken the form of a rod headed at one end and provided with a clamping 15 nut threaded on the other end, or merely a wire or rod inserted through central apertures in the end plates and bent over at its ends. It is evident that tie rods having threaded portions are weaker at the thread- 20 ed part of the rod and must therefore be made of a relatively larger cross section in order to provide the necessary tensile strength effectively to clamp the closures to the roll. Considering the many thousands 25 of such rods used, a slight saving in the weight of each creates an appreciable saving not only in the cost of material but also in freight costs. With the wire type of rod bent over at its ends, it is apparent that to 30 attach the closures with such a rod under tension, would require a cumbersome operation and could provide no greater tension than that which would tend to re-straighten the rod.

35 It is the general object of the invention to provide a new and improved end closure and tie rod construction for hollow rolls, economical of material and manufacture, readily attached, and rugged and effective 40 in use.

Another object is to provide an improved end construction embodying a pair of closures and a tie rod formed of stock of uniform section having deformed or upset portions arranged to clamp the closures on a roll with the rod under tension.

In pursuance of the foregoing objects, we aim to provide a pair of thin dished disks having central apertures therein together 50 with washers positioned against the outer

sides of the disks to reinforce them and a tie rod arranged to clamp the closures thus formed to the opposite ends of a roll and to secure packaged material within the bore of the roll, upset or widened portions of 55 the rod being positioned to clamp said washers against the disks and maintain the rod under tension.

Further objects and advantages of the invention will become apparent as the description proceeds.

In the drawings:

Figure 1 is a longitudinal central section of a tar paper roll ready for shipment, embodying the preferred form of the invention. 65

Fig. 2 is an enlarged fragmental section showing in detail the preferred arrangement of end closures and tie rod.

Fig. 3 is a view showing a manually operable 70 tool for attaching a closing means to a roll.

Fig. 4 is a side elevation of the tool.

Fig. 5 is a fragmental view showing the position of parts of the manually operable 75 tool upon the completion of the attaching operation.

While we have shown in the drawings and will herein describe in detail the preferred embodiment of the invention, it is to be 80 understood that we do not thereby intend to limit the invention to the specific form disclosed but aim to cover all modifications and alternative constructions falling within the spirit and scope of the invention as expressed in the appended claims. 85

In the drawings we have illustrated the preferred form of the invention as attached to a hollow roll 1 of tar paper or other fabric. Within this roll are shown a plurality of packages 2, 3 and 4 containing cement, nails, etc. intended for the application of the rolled material, which packages are preferably shipped in each individual roll as illustrated. 90

The closing means for the roll is shown as comprising a pair of dished end disks or plates 5 and 5^a, a pair of washers 6 and 6^a positioned against the outer sides of the plates, and a tie rod 7 arranged to clamp 100

the closures against the ends of the roll and to bind the packages 2, 3 and 4 against the inner wall of the roll so as to prevent the packages from moving about in the roll during shipment. The end closures are 5 preferably dished as illustrated in order to lend rigidity and to center the closures on the roll. To provide a head or anchoring means at one end, the tie rod is provided with deformed or upset portions 8 and 8^a be- 10 tween which the washer 6 is placed, the end disks being provided with apertures 10 therein of a size adapted to admit the upset portion 8^a of the tie rod so that the rod may be entered through the end closure 5, 15 thence through the bore of the roll and through the aperture in the opposing end closure, to place the washer 6 in abutment with the disk 5. The invention contemplates that with the rod so entered through the 20 closures and over the packages, the washer 6^a will be positioned on the rod adjacent the closure 5^a and that while the end 7^a (Fig. 3) of the rod is drawn outwardly relatively to the washer 6^a to clamp the closures to the 25 roll, the rod will be deformed or upset at 12 to secure the parts in this clamping relation.

Figs. 3 to 5 disclose a manually operable 30 tool adapted to draw or tension, upset and cut off the tie rod during the process of attaching the closures to a roll. Inasmuch as this tool is not claimed in this application, it will be described but generally. The tool 35 is shown in position against an end disk 5^a with a pair of upsetting jaws 13, 14, abutting the washer 6^a and arranged to upset the tie rod 7 immediately adjacent the washer at 12 and has a shear blade 15 operable to cut off the rod just outside of 40 the upset portion when the upset portion has been formed.

This tool comprises generally a head 16 upon which the jaws 13 and 14 and blade 15 are mounted and is provided with a pair 45 of tensioning rolls 17, 18. These rolls are preferably driven simultaneously and in opposite directions by intermeshing pinions 19, 20 and may be actuated by means including, 50 handle 21 mounted on one end of a shaft 21^a which when operated in one direction actuates the rolls to draw the rod outwardly of the roll. A suitable ratchet device (not shown) is provided intermediate the shaft 55 21^a and the rolls so that when the shaft is rotated in the opposite direction the rolls are held against reverse rotation to maintain the rod under tension.

The roll 18 is preferably corrugated and 60 the roll 17 is provided with a flat spot 22 so as to permit the insertion of the rod therebetween. Upon a rotation of the rolls with the corrugated roll turning in a counter-clockwise direction (Fig. 3) the rod is 65 gripped between the two rolls and drawn

outwardly from the washer 6^a, thereby clamping the end closures against the ends of the fabric roll with the upsetting jaws 13, 14 in abutment with the washer 6^a. The mechanism of the device is such that upon the completion of the tensioning operation the handle 21 may be rotated in the reverse direction to actuate the jaw 14 to upset the rod and to actuate the shear blade 15 to cut off the rod. This mechanism is herein shown as comprising generally arms 23, 24, connected respectively to the jaw 14 and shear blade 15 which arms are arranged to be actuated by cams 25, 26 driven by means of a worm 27 and worm wheel 28 on the 80 shaft 21^a.

To apply the device to a roll it is merely necessary to pass the tie rod through one disk to a position wherein the washer 6^a abuts the disk, then pass the rod through the bore of the roll and over the enclosed packages and place a second disk upon the extended portion of the rod. The disks may then be positioned centrally of the roll and, by means of a tool such as shown, the rod may first be tensioned to clamp the disks and packages against the roll and then upset and sheared off to retain the parts in that position.

It will be apparent that the tie rod disclosed herein can be cheaply manufactured from a wire or rod of uniform section and that because the operations performed upon the rod for adapting it to clamp the end closures are arranged to provide an effective clamping means without weakening the rod, a rod of minimum cross section may be used with washers positioned to reinforce the disks about their apertures. The disks also may be formed of a lighter material. It is contemplated that the device will be arranged for shipment to a paper factory with the end closures nested and the rods provided with the upset portions 8 and 8^a and washer 6 at one end thereof. This permits of a compact arrangement during shipment.

We claim as our invention:

1. A protective means for paper rolls having a central bore, comprising in combination a pair of apertured plates one for each end of the roll, a rod extending through said bore and having its opposite ends projecting through the apertures in the plates with upset heads on said projecting ends, and washers interposed between said heads and the outer sides of said plates, said heads being positioned on the rod so as to hold it under tension with the plates in firm contact with the ends of the roll, and said rod further having an upset portion spaced inwardly from one of said heads and adapted to retain one of said washers between it and the head before assembly of the rod in the roll.

2. A protective means for paper rolls having a central bore, comprising in combination a pair of apertured plates one for each end of the roll, a rod adapted to be passed through the central bore of a roll with its opposite ends projecting through the apertures in said plates when the latter engage with the ends of the roll, one of said projecting ends having means engaging with the plate to hold the rod against movement inwardly of the plate, and the other projecting end portion of the rod being deformed cross sectionally to provide an abutment acting against the plate adjacent thereto to hold the rod under tension.
